Patented Nov. 18, 1919.

UNITED STATES PATENT OFFICE.

SAMUEL C. MASON, OF LYNN, MASSACHUSETTS, ASSIGNOR TO VICTOR LAST COMPANY,
OF LYNN, MASSACHUSETTS, A CORPORATION OF MASSACHUSETTS.

RE-FORMED LAST AND PROCESS OF MAKING SAME.

1,322,253.

Specification of Letters Patent. Patented Nov. 18, 1919.

Application filed May 9, 1918. Serial No. 233,541.

To all whom it may concern:

Be it known that I, SAMUEL C. MASON, a citizen of the United States, and resident of Lynn, in the county of Essex and State of Massachusetts, have invented an Improvement in Re-Formed Lasts and Processes of Making Same, of which the following description, in connection with the accompanying drawings, is a specification, like letters on the drawings representing like parts.

In the manufacture of shoes the process of changing from one style of shoe to another necessitates the junking of the lasts on which the discarded style has been made and the purchase of a complete new set of lasts on which to manufacture the new style. The discarded lasts therefore become practically a dead loss even though they may be in a relatively sound condition and capable of giving satisfactory service for a long time. The loss thus involved seems particularly unnecessary since most changes in style involve merely relatively slight changes in the shape and dimensions of the parts of the last near the toe. Usually these changes in style consist merely in modifying the contour of the toe itself or in changing the outline of the outer edge of the forepart near the tip of the toe, or in minor variations in the width of the extreme toe portion of the last and the necessary modifications in the lines around the toe to agree with these changes in width.

The present invention aims to reduce the loss thus involved in changing from one style of last to another and it provides a novel last construction and a novel process of reforming or repairing lasts which enable a manufacturer to convert lasts of one style into lasts of a very different style at an expense which is very small indeed when compared with the cost of new lasts.

The manner in which it is proposed to accomplish this object will be readily understood from the following description and the novel features of the invention will be particularly pointed out in the appended claims.

Referring now to the accompanying drawings,

Figure 1 is a side elevation of a last embodying the present invention;

Fig. 2 is a side elevation showing a portion of a last undergoing the process of reforming or repair devised by this invention;

Fig. 3 is a plan view showing the last at a later stage in the process of reforming;

Fig. 4 is a plan view showing a last when this process has been substantially completed; and

Fig. 5 is a bottom view of the last shown in Fig. 4, but showing this last equipped with a reinforcing plate.

According to the present process the portion of the last in which the change in shape is to be made is first removed; a new piece is then inserted in the place of the part so removed and finally this piece is shaped to the required contour. As above stated, the style of the last is determined chiefly by variations in height, width and contour of the toe and in the shape of the outline of the last as it sweeps from the extreme tip of the toe back toward the little toe joint. Accordingly an asymmetrical portion of the last 2 including the outer side of the forepart, which portion determines the style of last, is cut away, as indicated in Figs. 2 and 3, preferably by a saw cut *a* starting from a point a short distance behind the toe and extending substantially parallel to the outer edge of the last and another saw cut *b* extending from this outer edge at an acute angle to the cut *a* and meeting this cut at a point to one side of the instep. A wedge piece 3 is then fitted into the notch so formed to take the place of the part that has been removed and is secured rigidly to the forepart of the last in any convenient manner, as, for instance, by glue. Preferably the grain in the piece so inserted runs lengthwise of this piece so that it will lie at an angle to the grain of the wood in the forepart and thus provide a stronger construction with which to work.

The last equipped with this wedge piece is next set into a last turning lathe and the toe portion is turned, the forward end of the repair piece 3 affording ample material for engagement with the dog of the lathe. The contour and style of the last will of course depend on the shape and style of the model used in performing the turning operation; and the repair part 3 affords abundant material with which to vary sub-

stantially the style given to the last, as indicated by the dotted lines in Fig. 3 which show two different contours that could be given to the toe part of the last. It is obvious that the style might be changed even more radically than in the manner indicated in Fig. 3. After the turning operation has been completed the last is finished in the usual manner and the toe portion of the last then appears substantially as shown in Figs. 1 and 4, the inserted piece being designated at 5.

It will readily be understood that this process is exceedingly simple and requires very little labor or new stock as compared with the labor and material required to manufacture a new last. Consequently the expense involved is relatively small. At the same time a very substantial and rigid construction is provided which will have practically as long a life, provided the remainder of the last is in sound condition, as would a new last. Since this process does not disturb any of the hardware with which the last usually is equipped no expense is involved in renewing this hardware. It will also be noted that the peculiar cuts made in the forepart of the last to receive the repair piece and the correspondingly peculiar shape of this piece, that is, the fact that it has a wedge shaped portion extending toward the heel of the last, are of practical advantage since the forces exerted on the last during the turning operation and during the manufacture of shoes on it tend to force the inserted piece into the recess or notch formed for it in the forepart of the last and thus assist in retaining this piece in its operative position instead of tending to remove it from this position, which might be the effect with a different construction.

As a further means of reinforcing the last, the bottom of the toe portion may be notched, as indicated at 6, Fig. 2, to receive a toe plate 7, Figs. 1 and 5, this plate having an outline conforming to the outline of the toe portion of the last and being secured both to the wood of the original last and also to the repair piece 5. A notch 8 is cut in the reinforcing plate 7 to permit the driving of the toe tack into the wood of the last at the point where the tack is usu-

ally inserted to secure the toe portion of the insole to the last.

What is claimed as new, is:

1. A last having a recess formed in the side of the forepart from top to bottom and across the toe portion, an insert set into said recess having a wedge-shaped portion extending toward the heel of the last with the surface of the insert coöperating with the surface of the adjacent parts of the last to form the upper supporting and sole supporting surfaces of the last.

2. A repaired last having a recess formed in the side of the forepart from top to bottom and across the toe portion, an insert set into said recess having a wedge-shaped portion extending toward the heel of the last with the surface of the insert coöperating with the surface of the adjacent parts of the last to form the upper supporting and sole supporting surfaces of the last, in combination with a toe plate fitted to both the insert and the adjacent part of the last and finished flush therewith at the rear of said plate.

3. A wooden last having a wooden insert set asymmetrically into the forepart of the last, the surface of said insert conforming to the contour of the adjacent parts of the last and coöperating with said parts to determine the style of the last, and a toe plate on the bottom of the last secured both to said insert and also to the adjacent part of the last.

4. The improved process of repairing a last which consists in forming a recess in the side of the forepart extending across the toe portion and from top to bottom of the last fitting a new piece in said recess having the grain of the wood extending differently from that of the last, securing of said insert and then shaping the inserted piece to conform to the contour of the adjacent parts of the last and then fitting a toe plate to both the insert and the adjacent parts.

In testimony whereof, I have signed my name to this specification, in the presence of two subscribing witnesses.

SAMUEL C. MASON.
